(57) **CLAIM**

The ornamental design for a chain holder, as shown and described.

DESCRIPTION

FIG. 1 is a front, top, left side perspective view of a chain holder showing a first embodiment of the design;

FIG. 2 is a front, top, left side perspective view of a chain holder as in FIG. 1;

FIG. 3 is a front, bottom, right side perspective view thereof;

FIG. 4 is a bottom view thereof;

FIG. 5 is a top view thereof;

FIG. 6 is a right side view thereof;

FIG. 7 is a left side view thereof;

FIG. 8 is a front elevation view thereof;

FIG. 9 is a rear elevation view thereof;

FIG. 10 is a front, top, left side perspective view of a chain holder showing a second embodiment of the design;

FIG. 11 is a front, top, left side perspective view of a chain holder as in FIG. 10;

FIG. 12 is a front, bottom, right side perspective view thereof;

FIG. 13 is a bottom view thereof;

FIG. 14 is a top view thereof;

FIG. 15 is a right side view thereof;

FIG. 16 is a left side view thereof;

FIG. 17 is a front elevation view thereof; and,

FIG. 18 is a rear elevation view thereof.

The broken lines shown in FIGS. 1-9 are for purposes of illustrating portions of the chain holder that forms no part of the claimed design; the additional broken lines shown in FIGS. 1 and 10 are for purposes of illustrating environmental subject matter only and forms no part thereof. The chain holder is shown in FIGS. 1 and 10 with a symbolic break in its length. The break line and the appearance of any portion of the article after the break line forms no part of the claimed design.

1 Claim, 16 Drawing Sheets
